UNITED STATES PATENT OFFICE.

JAMES THOMAS COOPER, OF LONDON, ENGLAND.

DESIGN FOR A SOCK-RETAINER FOR BOOTS AND SHOES.

60,012.

Specification for Design.

Patented Dec. 20, 1921.

Application filed August 11, 1921. Serial No. 491,589. Term of patent 14 years.

To all whom it may concern:

Be it known that I, JAMES THOMAS COOPER, a subject of the King of Great Britain and Ireland, residing at 63 Queen Victoria street, London, England, have invented a new, original, and ornamental Design for a Sock-Retainer, for Boots and Shoes, of which the following is a specification, reference being had to the accompanying drawing, forming part thereof.

The figure is a plan view of a sock retainer for boots and shoes, showing my new design.

I claim:—

The ornamental design for a sock retainer for boots and shoes, as shown.

Signed at London, England, this 21st day of July 1921.

JAMES THOMAS COOPER.
